Specification of Letters Patent. Patented Sept. 21, 1920.

Application filed April 23, 1915. Serial No. 23,322.

To all whom it may concern:

Be it known that we, LIBANUS M. TODD and CHARLES G. TIEFEL, citizens of the United States, and residents of Rochester, 5 in the county of Monroe, State of New York, have invented certain new and useful Improvements in Check-Writers; and we do hereby declare the following to be a full, clear, and exact description of the same, such 10 as will enable others skilled in the art to which the invention appertains to make and to use the same.

The present invention relates to machines for printing on commercial paper, such as 15 checks, drafts, and similar instruments, an assigned monetary value, in such an indelible manner as to insure protection against the alteration, or "raising" of the amount intended to be conveyed by the instrument. 20 This invention provides a machine constructed for the purpose of writing on commercial paper, by a protective method, any exact amount in dollars and cents which the instrument is intended to convey, as well as, 25 of course, any assigned limiting value which it may be desired to add for the protection of a simple inscription.

One object of the invention is the provision of a simple and convenient machine 30 of this type having a large number of type forms, available for printing a wide range of values, for the purpose of increasing the utility of the machine.

Another object of the invention is to provide a machine capable of printing a wide range of values, and at the same time compact in arrangement and of convenient size.

Other objects are to provide a new means for centering and locking the type forms in 40 printing position, a new platen operating device, and other features and advantages which are described in the following specification, reference being had by letters and numerals to the accompanying drawings forming a part of this specification, in which:—

Figure 1 is a top plan view of a check writing machine embodying the principles of the present invention.

Fig. 2 is a side elevation of the machine taken from the work receiving side thereof.

Fig. 3 is a bottom plan view, the bottom of the casing being removed to show interior parts.

Fig. 4 is a horizontal section, partly broken away, taken on the line 4—4 of Fig. 5.

Fig. 5 is a longitudinal vertical section on the line 5—5 of Fig. 4, partly broken away.

Fig. 6 is a transverse vertical section on 60 the line 6—6 of Fig. 5, showing the platen actuating mechanism.

Fig. 7 is a detailed view in horizontal section of a modified construction thereof.

Fig. 8 is in part an end elevation and in 65 part a transverse vertical section on the line 8—8 of Fig. 5, showing the means for actuating the presser-foot.

Fig. 9 is a transverse vertical section on 70 the line 9—9 of Fig. 5.

Fig. 10 is a plan of the type cylinder, showing the arrangement of the type forms thereon.

Fig. 11 is a diagrammatic view, showing 75 the principle of cooperation of the type cylinder and platen.

Fig. 12 shows one of the type forms enlarged.

Fig. 13 is an enlarged fragmentary view 80 of the platen.

Fig. 14 is an enlarged view showing the embossing of the paper along a printed line.

Fig. 15 is an edge view of the same.

Fig. 16 is a fragmentary top plan view 85 enlarged, showing the means for raising the presser foot.

Fig. 17 is a fragmentary view enlarged, showing the connection between the platen yoke and the rock shaft for operating it.

The same reference numerals are used 90 throughout to designate similar parts in the different figures of the drawings.

The present embodiment of the invention comprises a machine having a relatively shiftable type carrier and platen, the type 95 carrier having also a printing movement and having thereon a plurality of type forms arranged in lateral and longitudinal rows. By shifting the type carrier relatively to the platen, any lateral row of type forms may 100 be brought into position to cooperate with the platen during the printing movement of the carrier. The platen is moved into contact with the carrier, selectively, in timed relation to the rotation of the latter, to select, for printing impression, any desired type form in the lateral row thus presented. Thus the type forms may be brought, se-

lectively and individually into contact with the platen to produce a printing impression of any desired type form. To accomplish these results there is provided a main supporting frame of skeleton form, shown in Figs. 3 to 9, having ends 20 and 21 connected by a bottom cross rail 22 and by side cross rails 23 and 24. The frame is provided at each of its lower corners with a leg 25, (Fig. 6) having a recess 26 therein, with which engages a spring member 27 attached to a bottom plate 28 for holding the latter in position. Attached to the frame by means of screws 29 is a casing 30 inclosing the mechanism of the machine.

A small distance above the bottom cross rail 22 there is provided a pair of horizontal guard plates 32 and 33 placed close together and supported in position in the frame by four screws 31 at the corners of the latter. These plates 32 and 33 are provided for the purpose of guiding the paper to be printed upon in its passage through the machine. The lower guard plate 33 has a T-shaped opening 34 therein through one branch of which is adapted to be projected a platen wheel 35 having a serrated surface 36 and journaled upon a spindle 37 mounted in a yoke 38. This platen wheel is adapted to press in rolling contact against the type forms of a printing cylinder hereinafter described.

The yoke 38 is carried by an arm projecting from a sleeve 39, which is adapted to turn on a bushing 47 fixed by a pin 46 to a shaft 40. (See Figs. 3, 5, 9 and 17.) The latter shaft is adapted to rock in bearings 41 and 42 in a frame member 43 formed in the cross rail 22, and in a bearing 44 in an arm 45 which projects horizontally from the said cross rail. The bushing 47 has an arm 48 (Fig. 17) fixed thereto and projecting horizontally therefrom which carries a pin 49 and has a downwardly projecting outer end 48a. A spring 50 is connected at one end to the pin 49 and at its other end to a similar pin 51 in a lug 52a depending from one branch 52 of the yoke 38. The lug 52a has fixed thereto a pin 55 which projects into an elongated opening in the downwardly projecting outer end 48a of the arm 48 of the bushing 47 for serving together with spring 50 as an actuating connection between the arm 48 fixed to the rock shaft 40 and the yoke 38 carrying the platen. The branch 52 is extended into position to contact with the upper end of a screw 53, adjustably supported in a lug 54 of the frame member 43. The screw 53 is adapted to limit the downward movement of the platen carrying yoke 38 as the latter oscillates with the rock shaft 40.

The operation of the parts so far described is as follows:—As the shaft 40 is rocked by means hereinafter described, the

arm 48 fixed thereto is oscillated, and, by means of its connections with the yoke 38 oscillates the latter to project the platen wheel through and to withdraw it from the opening 34 in the lower guard plate 33. The spring 50 tends to normally hold the pin 55 in the upper part of the elongated opening 56 of the arm 48 so that the platen is actuated normally upward by means of the tension of the spring 50. Should the platen in its upward movement be forced too strongly against a type form or other unyielding material, the resiliency of the spring 50 will allow pin 55 to move across the opening 56 and the platen to yield and so prevent undue strain upon any part of the machine.

It is desirable to provide for a slight adjustment of the platen in the direction of its axis, and for this purpose the shaft 40 is permitted to have endwise motion in its bearings and an adjusting means is provided in the spindle 55a (Fig. 3), which has at one end a flange engaging in a recess in the sleeve 39, and at the other end a threaded portion adjustable in the frame member 43, so that the shaft 40 and parts carried thereby including the platen may be adjusted by turning the spindle 55a and locking it in adjusted position by means of the locking nut 55b.

The rock shaft 40 has fixed thereto at its outer end a lever 57 (see Fig. 6) which extends both above and below the shaft. The lower end of the lever 57 has attached thereto one end of a spring 58, the other end of which is attached to a pin 59 on the frame for holding the platen normally in a lowered or retracted position. The upper end of the lever 57 carries a pin 60 on which is journaled a roller 61. This roller serves as a follower for moving over the outlines of two cams, 62 and 63 fixed on a sleeve 65 (see also Figs. 4 and 5.) The cams are held a suitable distance apart by means of a spacing member 64, which is too low to contact with the follower. The sleeve 65 is slidable longitudinally on a shaft 66, but is fixed to rotate with the said shaft by means of a key sliding in the keyway 91. The sleeve 65 has a groove 65a engaged by a small roller 67 rotatably mounted on a pin 68 in the end of one branch of a bell-crank 69. The bell-crank 69 is pivoted at 70 on the main frame, and its other branch has pivoted thereto at 71 a link 72 which is pivoted at its other end 73 to an arm 74 fixed on a rock shaft 75 mounted above in the main frame. A member 76 is pivoted to the frame at 77 and carries at its other end a pin 78 adapted to engage in a series of recesses 79, 80 and 81 in the lower end of the arm 74. The pin 78 is urged into engagement with these recesses by a spring 82 attached at one end to a pin 83 on the member 76, and at its other end

to a pin 84 on the frame. The purpose of the pin 78 and the coacting recesses is to form a centering device for the arm 74 to mark its various positions.

5 It will be apparent from the above explanation that, as the shaft 75 is given a rocking movement the arm 74, by means of the link 72 oscillates the bell-crank 69 and so shifts the cam sleeve 65 to bring either of 10 the cams, or the spacing member 64 under the follower 61. When the spacing member 64 is thus brought under the follower 61, the platen actuating mechanism is in a neutral position and rotation of shaft 66 produces no actuation of the platen, so that the 15 type cylinder may be freely revolved for inking or cleaning the type. Referring to Fig. 6 it will be seen that the cams 62 and 63 are provided with respective high portions 62^a and 63^a extending over a small part of the circumference of each cam, and these cams are arranged relatively to each other at an angle of about 90 degrees. When either cam is opposite the follower 61, each 20 rotation of the shaft 66 will produce an oscillation of the lever 57 as the high portion of the cam passes the follower, and thus raise the platen connected therewith, in timed relation with respect to the rotation 25 of the shaft 66. It will be noted that each of the cams will thus produce an upward actuation of the platen in different timed relation with respect to each rotation of the shaft 66.

30 35 While the mechanism described above for timing the actuation of the platen is the form of construction now preferred by us, we have conceived of other means for producing the same result, one of which, shown 40 in Fig. 7, will now be described. In this form, instead of shifting the cams 62 and 63 by means of a sleeve sliding longitudinally of the shaft, these cams are mounted on a sleeve 190 which is fixed to the shaft 45 66 by means of a pin 190^a. The cams are held in spaced relation as before by means of the spacing member 64. The shaft 40 carries a lever 191 similar to the lever 57 of the preferred form, except that the upper 50 end of the lever 191 is formed into an elongated yoke 192 in the branches of which, and parallel to the shaft 66, is mounted a spindle 193. Slidably journaled on this spindle is a sleeve 194 having at one end a 55 roller cam follower 195 and at its other end a groove or circular recess 196 engaged by a small roller 197 journaled on the end of one arm of a bell-crank lever 198. This lever 198 corresponds with the bell-crank 60 lever 69 of the preferred form, having its other arm pivotally connected to the link 72. The actuation of the bell-crank lever 198 slides the cam follower 195 longitudinally 65 of the spindle 193 to aline it with either of the cams or with the spacing member 64, thus controlling the operation of the platen.

Referring to Figs. 9 and 17, it may be seen that by adjusting the screw 53 the amount of retraction of the platen may be 70 controlled at will and the usual adjustment allows the top of the platen to fall even with the lower guard plate 33, so that the platen will not obstruct the insertion of a sheet of paper. The same adjustment controls the 75 movement of the follower toward the shaft 66, and normally positions the follower so that it will not touch the spacing member 64 or the low portions of the cams, but only the high portions of the latter. This allows the 80 follower and cams to be freely shifted relatively to each other while the platen is inactive.

When the platen is moved upwardly to 85 produce a printing impression the top of the wheel projects through the lower guard plate and a slight distance through a slot 85 in the upper guard plate 32 and so carries the paper placed between the plates into contact with the printing cylinder 87. The 90 slot 85 is a trifle wider than the platen wheel so that the paper is not cut by any contact between these members, but the platen bends or draws the paper slightly into the slot and so raises or embosses in 95 the paper a narrow field upon which is the printed line. This will be made clear by an inspection of Figs. 14 and 15. One object attained by the embossing of this strip is to hold the inked portion of the paper out of 100 contact with the surface upon which it rests, to prevent smearing of the ink while wet.

The type cylinder 87 is mounted upon the shaft 66 journaled at its ends in the ends 20 and 21 of the main frame. The cylinder 105 100 has elongated bearings 88 and 89 at its ends upon the shaft 66 to adapt it for sliding longitudinally thereof, but a feather 90 projecting from the cylinder moves in a keyway 91 of the shaft to insure the rotation 110 of the cylinder with the shaft.

Referring to Fig. 10 it will be seen that the cylinder 87 has upon its surface a plurality of individual type forms 200, each extending circumferentially of the cylinder. 115 The type forms are arranged in two columns extending parallel with the axis of the cylinder and placed side by side in spaced relation. The type forms are of varying lengths and are arranged so that the ends 120 of the words in each column are in alinement in the direction of the axis of the cylinder, as shown at 201, and the forms are placed opposite each other in their respective columns so as to be in alinement 125 transversely of the axis of the cylinder. This arrangement brings the type forms into rows circumferentially of the cylinder as well as in the direction of its axis, and the forms are spaced from one another for 130

individual coöperation with the platen. The purpose of this relative arrangement of the forms will appear as the description proceeds.

- 5 A yoke 92 is also arranged to slide longitudinally of the shaft 66 having ends 93 and 94 journaled upon the shaft for this purpose. This yoke embraces the cylinder 87 and its ends are in contact with the ends 10 of the cylinder for the purpose of shifting the cylinder longitudinally of the shaft. The end 94 of the yoke like the end 88 of the cylinder, has an elongated bearing upon the shaft 66 so that it will slide smoothly 15 over the flanges or circumferential shoulders 95 upon the said shaft. These shoulders 95 are spaced longitudinally of the shaft to form between them a series of circumferential grooves 96. These grooves 96 are all of equal width and are spaced longitudinally of the shaft 66 to correspond with the longitudinal spacing of the type forms upon the cylinder 87, there being one groove 96 for each of the type forms.
- 20 The yoke 92 is held against rotation about the shaft 66 by means later to be described, and carries fixed thereto a small plate 98 which projects from the bearing in the end 94 of the yoke toward the shaft 66. The 25 inner end of this plate 98 is of such thickness as to fit closely within the grooves 96 upon the shaft and extends into proximity with the shaft at the bottom of the grooves. Each of the shoulders 95 extends only part 30 of the way around the shaft 66, as will be seen in Fig. 9, leaving a slideway 97 for the plate 98 in which the plate can move freely to allow the yoke to slide longitudinally of the shaft. The forward end 99 of each 35 shoulder 95, which is in advance as the shaft 66 is rotated in the direction shown by the arrow in Fig. 9, and the side of the plate 98 with which the end 99 first engages are beveled so that the plate will readily pass 40 from the slideway 97 into any one of the 45 grooves 96 as the shaft 66 is rotated.
- It is thus apparent that as the yoke and the cylinder embraced by it are shifted longitudinally and brought to a new position 50 on the shaft 66 the plate 98 will come to rest opposite one of the grooves 96. Then as the shaft is rotated the shoulders 95 adjoining this groove will embrace the plate 98 and thus lock the yoke and cylinder 55 against movement longitudinally of the shaft. The beveled ends on the shoulders and on the plate serve to center the cylinder with the selected type form accurately positioned opposite the platen 35.
- 60 The means for shifting the yoke 92 comprises a plate 100 (see Figs. 5 and 9) which is journaled on the end 94 of the yoke about its bearing on the shaft 66, so that the plate 100 may be oscillated in a plane at right angles to the shaft. This plate is securely held to the yoke by means of a pin 101 fixed to the yoke and extending through an elongated slot 102 in the plate, and also by a bar 103^a which is attached at its ends to an extension 94^a of the end 94 of the yoke 92 70 but is spaced therefrom to embrace the upper end of the plate 100 and hold it in contact with the end of the yoke as the plate 100 oscillates in a transverse plane. The plate has a slot 103 surrounding shaft 75 to allow 75 the transverse motion of the plate relatively to the shaft. The upper end of the plate 100 extends through a slot 104 in the top of the casing 30 and is bent at right angles in a horizontal direction, as shown at 105, to provide 80 for the attachment of an operating handle 106. By grasping this handle the operator can shift the yoke and cylinder longitudinally on the shaft 66 to any desired position.
- 85 Referring to Figs. 5 and 9, the yoke 92 has projecting upwardly therefrom a lug 118 positioned near and parallel with the extension 94^a of the end 94 of the yoke. This lug carries at its upper end a roller 90 116 journaled on a pin 117 fixed in the lug, and this roller moves in a longitudinal slot 115 in the frame attached to the casing 30 above and parallel with slot 104. The roller fits closely within this slot 115 and serves 95 to prevent any rotational movement of the yoke 92 about the shaft 66. The lug 118 and the extension 94^a of the yoke surround the shaft 75, which extends above the yoke parallel with the shaft 66. Mounted on this 100 shaft 75 is a collar 107 embraced between the lug 118 and the extension 94^a, and slideable along the shaft 75 as the yoke is shifted along the shaft 66. The collar however, carries a feather 108 which projects into a keyway 109 extending longitudinally of the shaft 75. The collar is thus held against rotation relatively to the shaft 75 and any oscillating movement imparted to the collar 105 will therefore be transmitted to the shaft 110 75. The collar carries on its upper side two spaced lugs 110 which engage either side of a small roller 111 journaled on the plate 100. By this means any oscillating movement given to the plate 100 by means of the operating handle 106 is transmitted to the collar 107, resulting in the rocking motion of the shaft 75. This rocking movement is 115 for the purpose of shifting the cam sleeve 65 by means of connecting mechanism which 120 has already been described.
- The upper horizontally extending end 105 of the plate 100 carries at either side upwardly extending spaced branches 113 and 114. Above the opening 104 is a dial plate 125 112 having arranged thereon in two columns, as shown in Fig. 1, a plurality of characters each of which represents character borne by a corresponding type form. The branches or index fingers 113 and 114 ex- 130

tend upwardly and inwardly toward the dial, having pointed ends adapted to be brought into register with the lines of characters upon the dial plate. As the handle 106 on the plate 109 is oscillated transversely, one or the other of the index fingers 113 and 114 is brought into proximity with the dial to register with the characters in the corresponding column thereon, while the 10 other finger is moved away from the dial. The two characters opposite each other in the columns on the dial are placed on the same line transversely of the dial so that the handle 106 may be moved longitudinally 15 of the dial to bring both index fingers opposite a selected character, and may then be oscillated transversely to bring one of the fingers into register with a selected character in one or other of the columns.

20 It will be understood from the above description that the movement of the handle 106 longitudinally of the dial to bring the index fingers opposite the line occupied by the character desired to be printed, and the 25 transverse movement of the handle to bring one of the index fingers into register with the selected character in its corresponding column will serve first to shift the printing cylinder longitudinally on the shaft to 30 bring the line of the selected type form into co-operative position relatively to the platen, and then to shift the cam sleeve to bring the proper cam into position for actuating the platen into selectively timed contact with 35 the individual type form desired to be printed during each rotation of the printing cylinder.

The main frame is provided with a bearing 119 (see Fig. 8) in which is journaled 40 a short shaft 120 extending at one end outside of the casing 30 and having fixed at this end a crank arm 121 carrying an operating handle 122. The inner end of the shaft 120 has pinned thereon a spiral gear 45 123 which meshes with a corresponding gear 124 fixed upon one end of the shaft 66. The rotation of the crank 121 thus rotates the shaft 66 and the type cylinder carried thereby to bring the desired type form into contact with the platen for making the printing 50 impression. A means is provided for securing shaft 120 against movement in the direction of its axis in the plate 125 adjustably attached to the frame by means of a 55 screw and entering a circumferential recess 126 in the shaft 120.

A similar means is provided for securing the shaft 66 in the plate 127 coacting with the groove 128 at the righthand end of this 60 shaft, as shown in Fig. 4. By means of these parts the gears 123 and 124 may be properly positioned relative to each other.

The inking of the type forms is accomplished by means of two inking rolls 129 65 and 130, extending parallel with the type

cylinder and in rolling contact therewith on either side. The roll 129 is removably journaled at its ends in open slots 131 upon the inner side of plates 132 which are pivoted at 133 on a lug of the type cylinder 70 yoke. The roll is held in contact with the type cylinder by means of springs 134 which are attached at one end to the plates 132 and at the other end to pins fixed on the yoke. The plates 132 may be swung away 75 from the cylinder to allow the removal of the roll 129. The roll 130 is removably journaled at its ends in open vertical slots 135 in plates 136 pivoted at 137 on lugs on the yoke. Journaled in the same slots 135, and 80 resting upon the inking roll 130 is an ink supplying roll 138. This roll 138 is held in the slot 135 and in contact with the roll 130 by plate 139 pivoted at 140 on the plate 136. The plate 139 has a forwardly extending 85 upper end engaging over the trunnions of the roll 138 for holding it in the described position, and the other end of the plate 139 has a rearwardly extending stop lug 141 adapted to engage a shoulder on 90 the plate 136. A spring 141^a is attached at one end to the yoke and at the other end to the plate 139 for pressing the upper end of this plate against the trunnions of the roll 138, and at the same time for swinging 95 plate 136 to such position as to hold the inking roll 130 in contact with the cylinder. Both rolls 129 and 130 are longer than the printing surface of the cylinder and their ends extend over the peripheries of disks 100 87^a on the ends of the cylinder.

The peripheral surface of these disks is a little below the surface of the type forms so that the type forms will engage the inking rolls as they are rotated past the latter, 105 but the inking rolls will be retained in their approximate inking position by contact with the disks 87^a when the cylinder is rotated to bring a portion of its surface not occupied by type forms opposite the inking 110 rolls.

The casing 30 is provided with a small door 142 opposite the supply roll 138 affording access to the interior of the casing. This door is particularly useful when it is 115 desired to reink the supply roll.

For guiding the paper during its passage through the machine and for preventing any inadvertent movement thereof, there is provided a presser foot 143 bearing resiliently 120 upon a roller 144, as shown in Fig. 9. The paper passes between these members which hold it on the lower guard plate and offer a frictional resistance to its motion. The member 143 is a plate journaled at 145 to 125 a lug 146 on the cross rail 23, and this plate is normally held pressed against the roller 144 by means of a spring 147 bearing upon the upper side of said plate and against the cross rail 23. The plate 143 is adapted 130

to be raised out of contact with the roller 144 for the purpose of the insertion of the paper by manual means now to be described.

Projecting through an opening in the end 5 of the casing 30 is a finger piece 158 attached to the end of the lever 159 which is fixed to a shaft 160 journaled in the end 20 of the frame and in a lug extending from the cross rail 23. The casing is provided 10 with an opening of sufficient size to allow of a small vertical movement of the finger piece 158 which produces a rocking movement of the shaft 160. The shaft 160 is provided opposite the presser foot 143 with 15 a spur 161 engaging loosely in an opening in the leaf 162 extending upwardly from the presser foot. By pressing downwardly on the finger piece 158 the shaft 160 is rocked and the presser foot is lifted out of 20 contact with the roller 144 by means of the connections described.

A means is provided for retaining the presser foot in raised position comprising an arm 163 (see Figs. 8 and 16) fixed to 25 the shaft 160 and having pivoted to its outer end a member 164 which is pivoted also at 165 to a link 166 pivoted in turn to the frame at 167. Pivotal mounted at 165 on the member 164 is a plate 168 having arms 30 extending upwardly and downwardly from its pivot. The upper arm 168^a is adapted to engage with the frame beneath the bearing 119 and is urged into such engaged relation by means of a spring 169 attached at one 35 end to the plate 168 and at its other end to the member 164.

It will be seen that as the finger piece 158 is depressed the member 168 is lowered. The spring 169 pulls the arm 168^a into engagement beneath the frame so that the finger piece 158 is retained in its lower position and the presser foot is held out of contact with the roller. In this position the check or other paper may be inserted between the presser foot and roller into printing position, and an automatic means is provided to insure the release of the presser foot at the commencement of the printing operation comprising a cam 170 fixed to the 40 shaft 66 in position to coöperate with the lower arm 168^b of the member 168.

The cam 170 has a flat portion which comes into contact with the arm 168^b when the cylinder is rotated to inoperative position for the insertion of the check. This position permits the operation of the means for retaining the presser foot raised, as explained above, but when the shaft 66 is rotated to produce a printing impression the 45 high portion of the cam 170 turns into engagement with the arm 168^b at a time just previous to the movement of the type into contact with the paper and serves to oscillate the member 168 about its pivot 165, 50 moving the arm 168^a out of contact with

the frame and so allowing the presser foot to descend and engage the paper. This mechanism requires but one actuation for each printing operation. That is, the member 158 is pressed downwardly when the 55 paper is first inserted in the machine and the presser foot is then automatically thrown into operation by the commencement of the printing operation. The presser foot is not again adjusted until the desired printing has 60 been accomplished, when the presser foot may be raised by means of the finger piece to withdraw the check. The presser foot is then left in this position ready for the insertion of a new check. 80

The roller 144 (see Figs. 3 and 9) is rotatably journaled at its ends in a member 171 supported upon the frame member 43 of the cross rail 22. The member 171 is attached to the frame 43 at each end by means 85 of screws 172 and 173 which have a close fit in member 171. The screw 173 is a close fit in the opening provided for it in the frame 43, but the screw 172 passes through a slot in the member 43 so that the member 90 171 carrying the roller may be turned a slight distance about the screw 173 as a pivot. For accomplishing this adjustment there is provided a bar 174 pivoted on the screw 173 and snugly engaging the screw 95 172, and this bar carries at its end near the latter screw a projecting lug 175. This lug extends into a recess in the head of a screw 176, so that by turning the screw 176 the bar 174 is turned a slight distance about 100 the screw 173, and by means of the connecting screw 172 turns with it the member 171, thus adjusting the direction of the axis of the roller 144.

Referring to Figs. 2 and 6, the paper to 105 be printed upon is inserted in the machine through a long slot 179 in the casing 30 at the righthand side of the machine, as seen in Fig. 6, and passes out of the casing on the opposite side through a slot 179^a. Attached to the casing and extending over the slot 179 opposite the printing point is a gage plate 202 having therein a sight opening 203 for properly positioning a check on a sliding table 180 provided in front of the feed 110 115 opening 179 for supporting and guiding the paper in its passage through the machine. The table is provided with brackets sliding upon rods 182 supported by the frame of the machine, and carries a guide 181 extending vertically at one side of the table which serves as a means for guiding the paper. There is also provided a gage bar 183 slidably attached to the under side of the table by means of a pin 185 projecting from the 120 table through a slot in the bar 183 and also through a keeper plate 186. The bar 183 is provided at its end with an upwardly extending flange 184 and may be slidably extended toward and from the table and 130

also turned parallel with the table to place it out of the way when not in use, in the position shown by dotted lines in Fig. 3. The gage bar is adjusted for any given size 5 of check so that when the check is placed upon the table, as shown by dotted lines in Fig. 1, with one end against the flange 184, the inner side of the check is in proper position between the type cylinder and platen 10 for beginning the impression of a printed line.

As already pointed out the platen wheel is provided with a series of circumferential ridges and depressions upon its surface, as 15 illustrated in detail in Fig. 13, and the type forms have their surfaces provided with corresponding ridges and depressions as illustrated in Fig. 12. The platen is so adjusted longitudinally of the type cylinder that 20 whenever a type form is locked in position to register with the platen each projecting ridge of the latter coöperates with a groove or depression in the surface of the type form. This construction of the surfaces of 25 the type forms and platen serves to disrupt the fibers of the paper passing therebetween simultaneously with the making of the printing impression so that the ink is pressed into the disrupted fiber and impregnates 30 the paper beneath its sizing, and thus incorporates the characters into the body of the paper itself.

The rolling contact of the type forms with the platen feeds the paper forward 35 automatically during the printing impression, and also provides an additional feeding movement at the end of each word for producing a space between this word and the succeeding one. This latter effect will 40 be understood by referring to Fig. 11, wherein is shown a diagram illustrating the theory of coöperation of the serrations of the printing couple. The lines AA and BB represent the surfaces of contact which the 45 printing couple and platen would have respectively if their peripheries were smooth surfaces. These surfaces are in contact at but one point, which is on the line of centers DD. The lines aa and bb represent the outer 50 lines of the projecting ridges, and the line CC represents the path of movement of the paper. As the paper is fed forward it is engaged by the projecting ridges on the serrated surfaces of the printing couple at a 55 point on the line FF, these members turning in the direction indicated by the arrows. The printing impression is produced approximately at the line DD, but any given part of the paper which is impressed at DD 60 continues to be fed forward to a point represented by the line EE by the coöperative frictional action of the ridges and grooves on the printing couple. Thus as any type form rolls over the platen until its termination reaches the line DD, the end of the cor-

responding word impressed upon the paper is fed forward from DD to EE as this type form passes out of contact with the platen. The succeeding word will begin at FF as the new type form first comes into contact with 70 the paper at this point. This leaves a space between the words corresponding to the distance from the line EE to the line FF.

The extent of this space between the words is dependent not only upon the design 75 of the serrations of the printing couple but also upon the time at which the platen moves out of contact with the printing cylinder corresponding to the time at which the follower rolls off the high portion of 80 the actuating cam 62 or 63. If the cam be advanced slightly the platen will move out of contact with the printing cylinder before the end of the printing impression has moved the whole distance from 85 DD to EE. Since a single cam actuates the platen for each column of type forms on the printing cylinder, the words of each column all terminate in the same longitudinal line as previously described, so that the space 90 produced at the end of every type form may be regulated by a proper setting of the cams.

This provides one method of regulating the spaces between words. There is, however, another factor controlling this effect 95 which is the resisting drag upon the paper of the spring presser foot. As the feeding actuation of the paper by the type form ceases, the inertia of the paper tends to prolong its motion, and the presser foot overcomes this motion of the paper by its frictional resistance in coöperation with the roller 144. The spacing distance may also be varied, therefore, by changing the pressure of the presser foot so that by these various means the spacing distance between 100 words may be fully controlled.

On reference to the dial it will be noticed that the words "Dollars" and "Cents", and the line of stars or asterisks, are written in a 110 single column at the bottom of the dial with index lines on both sides to indicate that each of these characters occurs in both columns on the type cylinder on the same circumferential line, so that when the index 115 fingers are brought opposite one of these characters on the dial the handle 106 may be shifted either to the right or to the left to print the given character.

The operation of the machine will now 120 be understood from a brief description. The gage bar having been adjusted for the length of check to be used, to bring the point on the check at which it is desired to start the impression in position between the 125 printing couple, and the presser foot having been raised by means of the finger piece 158, the check is placed upon the table in the position indicated by the dotted lines in Fig. 1, with its top resting against the flange 130

181 and its righthand end against the flange 184. The table is slid along the guide rods 182 until the desired line for the impression appears through the opening 203 in the 5 sight leaf. The index fingers are then moved along the dial to a position opposite the first character to be impressed, which is usually a line of stars. This shifts the type cylinder to bring the corresponding 10 type form opposite the platen. Since this character is provided in both columns of the type cylinder it is immaterial whether the handle 106 is shifted laterally to the right or to the left. The rotation of the 15 crank 122 is then started and the presser foot is immediately released automatically to guide the paper, before the type form moves into contact with it. The continued rotation of the crank then revolves the type 20 cylinder until the selected type form rolls over the platen and impresses the paper. If the amount desired to be written is, say \$325.75, the index fingers are then shifted along the dial until in line with the number 25 3 thereon in the lefthand column, when the handle is shifted toward the right to bring the lefthand index finger into register with the number 3. As before, the type cylinder is thereby shifted longitudinally to bring 30 the selected type form into coöperative position relatively to the platen, and the lateral shifting of the handle shifts cam 63 in position to actuate the follower. As the crank is then rotated the cylinder revolves 35 and the platen moves toward the latter as the first column comes over it and produces an impression of the character "Three". In a similar manner the proper index finger is brought into register successively with 40 the word "Hundred", the number 20, the number 5, the word "Dollars", the number 70, the number 5 and finally the word "Cents" each adjustment of the handle 106 being followed by a revolution of the crank 45 122. In each case the shifting of the handle 106 up and down the dial brings the selected type form into coöperative position relatively to the platen and the lateral shifting of the handle positions the proper cam under the follower for moving the platen into 50 contact with the selected type form as its column passes the printing point. At the end of each impression the platen drops back into inactive position. In this manner 55 the line of characters is printed and when completed the presser foot is raised by means of the finger piece 158, and the check is withdrawn at the lefthand side of the machine.

60 While the present embodiment of the invention has but two columns of type forms on the printing cylinder, it is obvious that, by a continued application of the same principle, three, four or more columns of type 65 forms on the same cylinder may be em-

ployed, a platen actuating cam being provided for each column in the manner herein shown and described.

Having thus described our invention, what we claim as new and desire to secure 70 by Letters Patent is:—

1. In a printing apparatus, the combination of a rotary type carrier provided with a plurality of type forms; a rotary platen, said type forms and platen being movable 75 toward and from each other and being each rotatable in engagement with the other to impress and feed the work; selecting mechanism for effecting a relative selective movement of the type forms and platen; operating means for rotating the type carrier; and means actuated by said operating means for effecting said movement of the type forms and platen toward and from each other, said latter means being variably controlled by said selecting mechanism. 80

2. In a printing apparatus, the combination of a rotary type carrier provided with a plurality of separate type forms; a platen rotatable in engagement with said type forms, said carrier and platen having a relative printing movement toward and from each other during the rotation of said carrier; selective means for effecting a relative movement between said carrier and 90 platen to select one of said type forms for coaction with the platen; and means for rotating said carrier and bringing the selected type form and platen into rotating engagement with each other to print and feed 100 the work, comprising a device set through the instrumentality of the selective means to vary the time of said relative printing movement of the carrier and platen in accordance with the type form selected. 105

3. In a check writer, the combination with a platen, of a rotary type cylinder having thereon a plurality of type forms arranged in a plurality of columns placed side by side, means for shifting the cylinder selectively in either direction parallel with said columns to bring the desired type form and platen into coöperative relationship and for controlling the time of operation of the platen, and means for rotating the cylinder 110 and actuating the platen into rolling contact with the selected type form. 115

4. In a check writer, the combination with a rotary type cylinder having a plurality of type forms arranged in a plurality of columns placed side by side on the cylinder, of a platen common to said type forms, selective means for effecting a coöperative relation between said platen and the type forms of each column, and means for actuating the 120 platen into rolling contact with any selected type form as the corresponding column passes the printing position. 125

5. In a check writer, the combination with a plurality of type forms arranged in two 130

columns placed side by side, the type forms in each column being in alinement with the corresponding type forms of the other column so as to form rows transversely of said 5 columns, of a platen rotatable in printing contact with said type forms, individually, said platen and type forms having a relative selective movement longitudinally of the columns to bring the platen and any one 10 of the transversely extending rows into co-operative relation, and having also a relative selective movement transversely of the columns and toward and from each other to bring the platen and any desired type 15 form of the selected row into rolling contact to print and feed the work.

6. In a check writer, the combination with a type carrier having a plurality of type forms thereon arranged in two columns, 20 side by side, the type units of each column being arranged in transverse alinement with respect to corresponding units of the other column, of a platen adapted for alinement with but one unit of either column at 25 a time and adapted to coöperate with the carrier by a rolling printing contact in a direction transverse to the rows of forms, the carrier and platen being shiftable relatively to establish such alinement, and a 30 selecting device embodying an operating member having one movement to aline the platen with two type units in the respective columns and another movement to control the printing contact of the platen with one 35 or another of such two type units.

7. In a check writer, the combination with a rotary shaft, a type cylinder fixed to rotate therewith but shiftable longitudinally thereof and having a plurality of type forms 40 arranged in a plurality of columns placed side by side on said cylinder, and means for rotating said shaft, of a rotary platen, and selectively variable means actuated by the 45 rotation of said shaft for moving the platen into contact with a type form in a selected one of said columns during the revolution of the type cylinder.

8. In a check writer, the combination with a rotary shaft, a type cylinder shiftable longitudinally of said shaft but fixed to rotate therewith and having a plurality of type forms thereon, arranged in a plurality of columns placed side by side on said cylinder and means to rotate the latter, of a rock 55 shaft, a rotary platen carried eccentrically thereby, and means connecting said rotary shaft and rock shaft to rock the latter, selectively, at a predetermined point in the rotation of said rotary shaft to move the 60 platen into contact with a selected type form in any column of the type cylinder.

9. In a check writer, the combination with a rotary shaft, a type cylinder fixed to rotate therewith but shiftable longitudinally 65 thereon and having a plurality of type forms

thereon arranged in a plurality of columns placed side by side on said cylinder, a cam sleeve having a plurality of cams and fixed to rotate with said shaft, but shiftable longitudinally thereof, and means to rotate said 70 shaft, of a rock shaft, a platen carried eccentrically thereby, an arm fixed to said rock shaft and carrying a follower adapted to contact with the cams on the cam sleeve, and means to shift the latter to bring any 75 cam, selectively, into coöperation with the follower to actuate the rock shaft and move the platen into contact with a selected type form in any column on the type cylinder.

10. In a check writer, the combination 80 with a type cylinder provided with a plurality of type forms, of a platen common to said type forms, selective means for shifting the cylinder and platen relatively to each other, means for effecting a printing 85 movement of the cylinder, and shiftable means for varying the time of operation of the platen with relation to the printing movement of the cylinder having a neutral position for maintaining the platen inoperative 90 during the printing movement of the cylinder.

11. In a check writer, the combination with a type cylinder provided with a plurality of type forms, of a platen common 95 to said forms, selective means for shifting the cylinder and platen relatively to each other, means for effecting a printing movement of the cylinder, and mechanism for controlling the operation of the platen comprising a shiftable member having a neutral position for maintaining the platen inoperative, and a plurality of active positions for varying the time of operation of the platen 100 during the printing movement of the cylinder.

12. In a check writer, the combination with a relatively fixed platen, of a rotary and longitudinally shiftable cylinder having a plurality of type forms arranged thereon 110 in lateral and longitudinal rows, means for rotating the cylinder, adjustable platen actuating means, and a single operating member for sliding the cylinder to bring the type forms of any lateral row into co-operative relationship with the platen, and for setting the adjustable means for actuating the platen into contact, selectively, with a form of said lateral row lying in any longitudinal row, for producing an impression 115 of any selected type form.

13. In a check writer, the combination with a platen, of a shaft, a rotary type cylinder shiftable longitudinally thereof and having a plurality of type forms arranged in 120 columns extending side by side on said cylinder, means for timing the contact between the platen and cylinder relative to the rotation of the latter, and a single operating member, connected to the cylinder to slide 130

the same relatively to the platen, and to the timing means to actuate the latter, to effect the contact of the platen with the selected type form as the latter passes the printing point.

14. In a check writer, the combination with a platen, of a rotary shaft, a type cylinder mounted thereon and having a plurality of type forms spaced longitudinally of the cylinder, the said cylinder being fixed to rotate with the said shaft but slideable longitudinally thereof to bring any type form, selectively, into coöperative position relatively to the platen, a shifting member for sliding the cylinder, and coating means on said shaft and shifting member to automatically position and lock the selected type form relatively to the platen as the said type form and platen move into contact.

15. In a check writer, the combination with a platen, of a rotary shaft, a type cylinder mounted thereon and having a plurality of type forms spaced longitudinally of the cylinder, the said cylinder being fixed to rotate with the shaft but slideable longitudinally thereof to bring any type form, selectively, into coöperative position relatively to the platen, a yoke held against rotation but slideable on the said shaft to shift the cylinder, a plate fixed on said yoke and bearing upon said shaft through a portion of its circumference, and beveled shoulders on said shaft extending through a portion of its circumference in axial alignment and spaced axially to correspond with the spacing of the type forms, said shoulders being adapted to embrace the said plate for a part of the rotation of said shaft to center and lock a selected type form in coöperative relation with the platen.

16. In a check writer, the combination with a rotary type carrier having thereon a plurality of type forms arranged in a plurality of circumferentially extending rows, and a platen, said carrier and platen being relatively movable to bring the latter and said circumferentially extending rows selectively into coöperative relation, and means to rotate said carrier, of a plurality of timing means for effecting printing contact between the platen and any type form of the selected circumferentially extending row during the rotation of said carrier, a selecting device for bringing into operation any one of said timing means, and a dial adapted to register the movements of said selecting device.

17. In a check writer, the combination with a type selecting device embodying an operating member having two movements, one to select one of a plurality of groups of types, and the other to select a single type unit of the selected group, of a dial having characters thereon corresponding to the types arranged in rows, and an index con-

nected to said operating member to move longitudinally of said rows of characters on the dial with the first mentioned movement of said member to indicate the group of types selected thereby.

18. In a check writer, the combination with a type selecting device embodying an operating member having two movements, one to select one of a plurality of groups of types and the other to select a type unit of that group, of a dial having two sets of characters arranged in rows, and an index connected to the said operating member to move longitudinally of the rows of characters on the dial with the first mentioned movement of the member and laterally into coöperation with a character in one or the other of the rows with the last mentioned movement of the member.

19. In a check writer, the combination with a plurality of type forms arranged in longitudinal and transverse rows and a platen adapted for individual contact with the type forms, said platen and type forms having a relative shifting movement in the direction of the longitudinal rows to select one of said transverse rows for coöperation with the platen, and having also a relative printing movement to select one of the type forms of said transverse row and bring it into printing contact with the platen; of a dial having characters thereon corresponding in arrangement to the type forms, and a type selecting device comprising an operating member provided with an index and having a movement to bring said index into registry with a transverse row of the characters and to effect the first mentioned selection, and having also a movement to bring said index into registry with a character of said transverse row and effect the second mentioned selection.

20. In a check writer, the combination with a casing, a dial thereon, an index finger movable over the dial, a platen, a shaft, a rotary type cylinder slideable longitudinally of the shaft and having a plurality of type forms arranged in columns extending side by side axially of said cylinder, means for selectively timing the contact between the platen and cylinder during each rotation of the latter and a single operating member connected to the cylinder to slide the latter relatively to the platen and to the timing means to set the latter, and to the index finger to move the latter over the dial, for effecting and indicating the contact of the platen with the selected type form.

21. In a check writer, the combination with a platen, of an axially shiftable type cylinder having a plurality of type forms arranged in axial and circumferential rows, a shifting member engaging said cylinder to shift the latter, means for selectively timing

the actuation of the platen, an auxiliary rock shaft, actuating connections from said rock shaft to said timing means, and a single pivoted operating member connected to 6 said shifting member to shift said cylinder and to said rock shaft to adjust the timing means for effecting a selective contact between any type form and the platen.

22. In a check writer, the combination 10 with a platen, of a shaft, a rotary type cylinder having a plurality of type forms arranged in a plurality of columns extending side by side axially of the cylinder, said cylinder having a shifting movement longitudinally of the shaft to bring any type form and the platen into coöperative relationship, means on said shaft for selectively timing the actuation of the platen, an auxiliary rock shaft having connection with 15 said timing means for adjusting the latter, and an operating member connected with said cylinder to shift the latter and with said rock shaft to adjust the timing means, for bringing the type forms, selectively, into 20 printing contact with the platen.
23. In a check writer, the combination of 25 a type carrier provided with a plurality of type forms, a platen common to said type forms, selecting mechanism for effecting a shifting movement of the carrier to bring any selected type form and the platen into coöperative relation, an inking device comprising inking surfaces for the type forms movable with the carrier during the 30 shifting movement thereof to maintain a fixed inking relationship between certain of the type forms and corresponding inking surfaces, actuating means for rotating the type carrier, and means actuated thereby 35 for moving the selected type form and 40 for moving the selected type form and

platen relatively into printing contact, one of said means being variably controlled by said selecting mechanism.

24. In a check writer, the combination 45 with a rotary type cylinder, of a rock shaft, a sleeve rotatably mounted thereon and having an arm, a platen rotatably mounted on said arm and adapted for printing contact with the cylinder, an arm fixed to said rock shaft, and a resilient connection between 50 the arm on the sleeve and the arm on the shaft whereby movement of said rock shaft moves the platen with yielding pressure into contact with said cylinder.

25. In a machine of the class described, 55 the combination with a type carrier having a plurality of groups of type forms thereon, of a platen common to the type forms and constructed to coöperate singly with said forms, a manipulative device operable to 60 determine both the group and the type form in said group to be printed from and means for effecting printing engagement of the platen and selected type form.

26. In a machine of the class described, 65 the combination with an operating member having an invariable extent of movement at each operation, of a plurality of groups of type forms, a manipulative device and means controlled thereby for determining 70 both the group and the form in the group to be printed from, a platen actuated by the operating member and means controlled by the aforesaid manipulative device for effecting actuation of the platen at different 75 points in the movement of the operating member.
